HAIR WAVE HOLDER

Filed Nov. 9, 1929

By Emil F. Lange

Inventor
Nell Fulton,

Attorney

UNITED STATES PATENT OFFICE

NELL FULTON, OF NEW YORK, N. Y.

HAIR WAVE HOLDER

Application filed November 9, 1929. Serial No. 405,983.

The present invention relates to hair dressing devices, and more particularly to a device for use on the hair after wavers and other hair forming devices have been removed for the purpose of holding the hair in set position.

An object of the present invention is to provide a holder adapted for engagement with the hair to hold the same in waved form after the wavers have been removed, and to provide a holder which is relatively flat, which conforms to the shape of the head, and which has no projections or extensions to injure the head or catch in objects surrounding the head, and a holder which may be quickly and easily applied and removed.

Another object of the present invention is to provide a relatively broad flat resilient holder which may be easily sprung apart and engaged over the hair which is to be held in shape so that the device will not only hold the hair but will also lie flat against the head and cause no discomfort when the wearer is lying down, and which has no parts which protrude either toward the head or outwardly therefrom.

A further object of the present invention is to provide a holder of this character which may be provided with fastening means at its free end for yieldingly holding the ends together so as to firmly clamp the arm of the device against the opposite sides of the hair, the improved fastening devices admitting of the quick and easy separation of the free end of the device so that it may be opened without the exercise of any undue skill or pressure.

The above, and various other objects and advantages of this invention will in part be understood from, and in part be described in the following detailed description of the present preferred embodiment, the same being illustrated in the accompanying drawings, wherein:

Figure 1 is an edge elevation of a hair holder constructed according to the present invention.

Figure 2 is an upper or outer side elevation of the holder, showing the relative width thereof.

Figure 3 is a perspective view of a slightly modified form of the wave holder in open position.

Figure 4 is a transverse section taken through the outer end of the wave holder of Figure 3, closed and showing the fastening means therefor.

Figure 5 is a perspective view of another modified form of the clip, showing a modification in the fastening means for the free ends of the clip, the clip being shown in open position.

Figure 6 is an enlarged fragmentary inner face view of the outer arm of the clip, showing the over-turned tongue at one side of the arm, and

Figure 7 is a cross-sectional view taken through the outer end portion of the clip when closed, showing the over-turned tongue in engagement with the inner arm of the holder.

Referring now to the drawings, and first to Figure 1, 10 and 11 designate the leaves or arms of the holder, the same being relatively flat and broad and adapted to engage against the opposite sides of the strands of hair to be clamped in position. The leaves 10 and 11 may be constructed of a single strip of metal overturned upon itself with the outer leaf or arm 11 slightly longer than the inner leaf 10 as shown in Figure 1, so that the outer end of the leaf 11 may be grasped by the finger for separating the leaves to apply and remove the holder. It will be noted that the holder is given a configuration which corresponds substantially to that of the side of the head so that the holder may lie flat against the head and conform to the hair configuration at the side of the head. The leaves or arms 10 and 11 are constructed and arranged so as to lie closely together and remain normally closed.

In the modification shown in Figures 3 and 4, one of the leaves or arms, preferably the arm 11 is provided upon its outer end with a pair of spring tongues 12 which may be integral with the arm 10 and disposed at the opposite sides thereof, the tongues 12 extending at substantially right angles to the leaf 10 and toward the leaf 11 and being sprung inwardly, as shown in Figure 4, so as to yield-

ingly engage the opposite edge portions of the leaf 11 near the extremity thereof.

The outer edges of the tongues 12 are rolled over outwardly to provide cam surfaces 5 against which the free end of the leaf 11 is adapted to engage for springing the tongues 12 apart to frictionally receive therebetween the free end of the arm 11.

The inner arm 10 of the holder, which is 10 adapted to lie beneath the hair and against the head, is preferably given the desired curvature of the head and is also preferably of a relatively stiff material, as indicated in Figure 4, so that the arm 10 will inherently remain in its curved form. The outer arm 11 is 15 more flexible and is adapted to be drawn downwardly toward the arm 10 and to be secured thereto without deforming the arm 10, the tongues 12 or other fastening devices used 20 holding the free end of the relatively flexible arm 11 over the hair and to conform to the general curvature of the arm 10.

As shown in Figure 3, the arms 10 and 11 25 may be formed of independent strips of metal which are secured together by rivets 13 or the like at the inner or closed end of the holder.

The modification shown in Figures 5, 6 and 30 7 relate to the structure of holding device for securing the arms 10 and 11 together in a closed position.

In this instance, the outer arm 11 is provided at one side with a tongue 14 which is 35 rolled over inwardly into hook form and extends a distance sufficient to firmly engage the under side of the arm 10 when the holder is closed. The arms 10 and 11 are of sufficient length to admit of the relative edgewise sliding movement of the arms at their free ends so as to engage and disengage the free 40 end portion of the arm 10 with respect to the tongue or hook 14.

In the use of the device, when the hair waver or other implement is removed from the hair, and it is desired to hold the hair in 45 such set shape without the use of the hair waver, the holder of this invention is opened so as to spring apart the arms 10 and 11 and the latter are engaged over the hair with the flat arm or leaf 10 toward the head 50 and with the arm 11 over the outer side of the hair. The holders are closed to firmly clamp the hair, and when a plurality of holders are to be used the same are secured to the layer of hair at spaced apart points.

Where the holder of Figures 1 and 2 is employed the inherent resiliency of the arms draws the holder to a closed position and maintains it clamped on the hair.

Where the modified form of the holder, 60 shown in Figures 3 and 4, and in Figures 5, 6 and 7, are used the tongues 12 or 14 for securing the free end portions of the arms 10 and 11 in clamping engagement with the hair.

It is obvious that various changes and modifications may be made in the details of con-

struction and design of the above specifically described embodiment of this invention without departing from the spirit thereof, such changes and modifications being restricted only by the scope of the following claims.

What is claimed is:-

1. A hair wave holder, comprising a pair of long flat leaves connected together at one end and disposed to lie in substantially face to face contact throughout their entire length and with smooth, flat and uninterrupted outer surfaces throughout their entire length and curved from end to end to substantially conform to the curvature of the head, one of said leaves having a pair of spring tongues at its free end in registry with the free end of the opposite leaf to receive the same and frictionally hold the leaves in closed position, the holder adapted to be fitted to the hair with the flat leaves engaging at opposite sides of a layer of the hair to clamp the same between the leaves and hold the hair in place.

2. A hair wave holder, comprising a pair of long flat leaves connected together at one end and disposed to lie in substantially face to face contact throughout their entire length and with smooth, flat and uninterrupted outer surfaces throughout their entire length and curved from end to end to substantially conform to the curvature of the head, one of said leaves having at one lateral edge and near its free end a tongue overturned upon said leaf and spaced therefrom a distance equal substantially to the thickness of the opposite leaf and adapted to receive the free end portion thereof beneath the tongue, the holder adapted to be fitted to the hair with the flat leaves engaging at opposite sides of a layer of the hair to clamp the same between the leaves and said second leaf adapted to be sprung in an edgewise direction for engagement beneath said tongue to clamp the leaves together.

3. A hair wave holder comprising a pair of long flat leaves connected together at one end and disposed to be in substantially face to face contact throughout their entire length and with smooth, flat and uninterrupted outer surfaces throughout their length, said smooth, flat and uninterrupted outer surfaces permitting the wearer to lie down without discomfort, and curved from end to end to substantially conform to the curvature of the head, the holder adapted to be fitted to the hair with one flat leaf engaging beneath a layer of hair and the other flat leaf extending across the outer side of the layer of hair to clamp the same between the leaves and hold the hair in place.

4. A hair wave holder, comprising a pair of broad flat arms connected together at one end and biased into face contact throughout their entire lengths by the inherent resiliency of the arms and with smooth, substantially flat and uninterrupted outer surfaces

throughout their entire length and having a longitudinal curvature conforming to the contour of the head, said smooth, flat and uninterrupted surface permitting the wearer to lie down without discomfort, and said arms 5 adapted to be spread apart and slipped over a layer of hair and adapted to bind against the opposite sides of the hair and retain it in shape.

10 In testimony whereof I affix my signature.
